Attorney

UNITED STATES PATENT OFFICE.

WILLIAM W. SHONK, OF VANDALIA, ILLINOIS.

VALVE-GRINDING MACHINE.

Application filed August 7, 1922. Serial No. 580,086.

To all whom it may concern:

Be it known that I, WILLIAM W. SHONK, residing at Vandalia, county of Fayette, State of Illinois, a citizen of the United States, have invented certain new and useful Improvements in Valve-Grinding Machines, of which the following is a specification.

This invention relates to valve grinding machines and particularly to that class of machines adapted to grind poppet valves.

The primary object of my invention is the provision of an improved valve grinding machine wherein rotary motion of a shaft, driven by either a hand crank or motor, will be transformed into a combined oscillatory and reciprocating motion which will give a proper action to the valve on its seat during the grinding operation.

Other and further objects will be apparent from reading the specification.

Referring to the drawing wherein embodiments of my invention are illustrated,

Figure 1 is a side elevation of my improved hand operated grinder with the side plate removed to show the workings and showing parts in section.

Figure 2 is a view similar to Figure 1 but showing the parts in a different position,

Figure 3 is a view showing an assembly of the working parts without the casing, illustrating the operation of the parts.

Figure 4 is a sectional view on the line 4-4 of Figure 1,

Figure 5 is a sectional view of my electrically driven valve grinding machine.

Figure 6 is another sectional view of my electrically driven valve grinding machine.

Referring particularly to Figures 1 to 3, 15 designates the main-body portion or housing. Extending above and out of line with the center of the housing is a hollow bearing portion 16. In line with the bearing portion 16, but below the housing 15 is a bearing portion 17. Within the bearing portions and extending through the housing 15 is the main shaft 18. On the lower end of this shaft 18 is an enlarged portion 19 embodying a tool holder. In a slot in the tool holder 50 is the tool 20 which is secured in place by the screw 21.

Arranged about the bearing portion 17 adjacent the bottom, is a standard 22 having legs 23. Between the standard 22, at its upper end, and the bearing portion 17 is a

sleeve 24 having a flange 25 at its bottom which overhangs the standard 22. Above the standard 22 and about the sleeve 24 is a collar 26 which with the flange 25 forms a securing means for the standard 22. The 60 standard 22 fits the sleeve 24 loosely enough to permit free relative turning between these two elements.

By means of the set screws 27, which are threaded in the collar 26, and pass through 65 the sleeve 24, the height of the standard 22 relative to the housing 15 may be regulated. These set screws 27 impinge against the bearing portion 17. On the upper end of the bearing portion 16 is adjustably mounted a 70 handle member 28. This handle member has an opening of such size as to receive the bearing member 16 and is adjustably held on the latter by means of a set screw 29 which is threaded in the handle member 28. Between the upper end of the inside of the handle member 28 and the upper end of the shaft 18 is a spring 30 which normally tends to force the shaft downwardly. In operation, the valve tool 20 engages a slot in the 80 valve 31. Below the valve 31 is placed, during the grinding operation, a spring 32 which is weaker than the spring 30 so that the spring 30 can overcome the spring 32 when released to act in a manner to be described.

Within the housing 15, and adjacent the shaft 18, are four cam faces 33, 33', two on each side. Extending through the shaft adjacent the cam faces is a projecting rod 34 90 which is arranged, relative to the cam faces, so that when the shaft turns, the projecting ends of the rod 34 will ride upon the cam surfaces. This action causes an endwise movement of the shaft when rotation takes 95 place. At the same time, the spring 30 is compressed.

Mounted in the housing 15, and concentric therewith, is a shaft 35. The outer ends of this shaft are suitably journaled in the cover 100 plates of the housing. Fixedly mounted with relation to and upon the shaft 35 are trigger or trip members 36. These members are arranged upon opposite sides of the shaft 18 and have fingers 37 extending 105 therefrom and in position to engage and move the ends of the rod 34 up along the cams 33, 33'. The fingers 37 are arranged in a staggered relation to the fingers on the opposite side of the shaft 18 in order to pre- 110

vent a tendency to drive the shaft in both directions at the same time.

On the outer end of the shaft 35 is a hand crank 38 for imparting motion thereto.

In the practical operation of the device, the standard 22 is adjusted for height so that the tool 20 will have a downward pressure when the valve is on its seat—in other words, the projecting ends of the rod 34 will be above the point of joining of the cams 33 and 33'. The weak spring 32 is inserted to raise the valve off of its seat. After the valve grinding compound is placed on the valve and its seat and the valve grinder is in place over the valve, it is only necessary to turn the hand crank 38. This turning of the shaft 35, causes fingers of opposite sides alternately to engage the outer respective projecting ends of the rod 34. This causes the rod to first turn the shaft and then permit the spring 32 to lift the valve off its seat due to the riding of the rod 34 up on the cams 33, 33' and consequent compression of the spring 30. As the finger passes the end of the rod 34, the spring 30 forces the rod 34 to ride down until the valve is again forced to its seat. This lifting of the valve, of course, permits new grinding compound to come to the valve seat. An instant later the finger 37 on the opposite side engages the rod 34 to turn it and the shaft 18 in the opposite direction. At the end of this movement, it is again lifted, the valve rising off of its seat and again dropping back thereon when the finger 37 trips from the rod 34. The turning of the crank 38 causes a repetition of the cycle just described. If desired, in order to permit portions of the valve to reach new portions of the seat, the whole valve grinding machine may readily be turned during the operation. This is made possible by the nature of the mounting of the standard 22 on the bearing member 17, already described.

Referring now to the modification illustrated in Figures 5 and 6 where I have illustrated my electrically driven valve grinding machine, the parts 116, 117, 118, 119, 120, 121, 122, 123, 124, 125, 126, 127, 128, 129, 130, 133, 133', 134, 135, 136, and 137 are similar to the corresponding parts 16, 17, 18, 19, 20, 21, 22, 23, 24, 25, 26, 27, 28, 29, 30, 33, 33', 34, 35, 36 and 37 of Figures 1 and 2 and perform similar functions.

In the place of the crank 38, I have provided a worm gear 138 for driving the shaft 135. In the housing 115, I have journaled a shaft 140 upon which I have provided a worm 141 in position to drive the worm gear 138. At one side of the housing 115, I have provided an extension housing 142 into which the shaft 140 extends for connection to the armature of the motor 148. A cap

144 is secured to the extension housing 142 in a suitable manner and forms a bearing for the end of the motor armature shaft.

At a suitable point on the housing is located a hand switch by which the electric current to the motor may be turned on and off.

By varying the number of fingers 37 and 137, the number of working turns during a certain time, may be changed for a given rotary speed of the shaft 35 or the shaft 135.

The operation of the electrically driven grinder is similar to the operation of the hand grinder except that the power is furnished by the electric motor.

It is clear from the above description that I have provided a valve grinder which gives an oscillatory and reciprocatory motion to the valve, thus giving the proper grinding action and a lifting action to the valve whereby the grinding compound is permitted to get back onto the surfaces to be ground between each two strokes. This insures the grinding of the valve to its seat in the minimum time.

While I have described embodiments of my invention, I desire to have it understood that I do not limit myself to the exact structures shown and that modifications and changes may be made without departing from the spirit of my invention and within the scope of the appended claims.

Having described my invention, what I claim is:—

1. A valve grinder, comprising a main shaft, a valve turning means on the shaft, a second shaft, means for rotating the second shaft, means projecting from opposite sides of the main shaft, means projecting from the second shaft in position to alternately engage the projecting means on opposite sides of the main shaft and guides for imparting an endwise movement to the main shaft when the latter is rotated.

2. A valve grinder, comprising a housing, a main shaft mounted in said housing for endwise and oscillatory movement, a valve holding tool on one end of the main shaft, a spring at the other end of the main shaft and normally tending to force the shaft in the direction of the valve, projections extending on opposite sides of the main shaft, a second shaft, projecting fingers extending from the second shaft in position to alternately engage the main shaft projections, thereby imparting an oscillatory movement to the main shaft, inclined guide means in the path of movement of the main shaft projections, to impart an endwise movement to the main shaft when the latter is rotated.

In testimony whereof I hereunto affix my signature.

WILLIAM W. SHONK.
